United States Patent Office

Des. 218,968
Patented Oct. 20, 1970

218,968

LAWN SPRINKLER

Joseph R. Mango, Midlothian, and Robert M. Goodman,
Morton Grove, Ill., assignors to Sears, Roebuck and
Co., Chicago, Ill., a corporation of New York

Filed Sept. 2, 1969, Ser. No. 18,955

Term of patent 14 years

Int. Cl. D23—01

U.S. Cl. D23—7

FIG. 1 is a perspective view taken from one side of a lawn sprinkler embodying our new design;

FIG. 2 is a perspective view taken from one end thereof;

FIG. 3 is a perspective view taken from the end opposite that shown in FIG. 2;

FIG. 4 is a perspective view taken from the top thereof and

FIG. 5 is a perspective view taken from the bottom thereof.

We claim:

The ornamental design for a lawn sprinkler, substantially as shown.
